(57) **CLAIM**

The ornamental design for an orthodontic bracket, as shown and described.

DESCRIPTION

FIG. 1 is a perspective view of an orthodontic bracket showing my new design in an orthodontic environment;
FIG. 2 is an enlarged perspective view showing my new design;

FIG. 3 is a front elevational view thereof;

FIG. 4 is a left-side elevational view thereof;

FIG. 5 is a top plan view thereof;

FIG. 6 is a rear elevational view thereof;

FIG. 7 is a right-side elevational view thereof; and,

FIG. 8 is a bottom plan view thereof.

The dashed lines are included for the purpose of illustrating environment and form no part of the claimed design.
